UNITED STATES PATENT OFFICE

STEPHEN A. SLAUSON, OF CEDAR RAPIDS, IOWA

CLOTHES DRYING RACK

Application filed January 13, 1930. Serial No. 420,476.

This invention relates to clothes-drying racks, mainly for domestic use, and of a foldable type, occupying a minimum of space in the house, when not in use, and adapted to be stowed compactly for transportation.

A further object of my invention is to provide a clothes-drying rack structure including a support and a pair of plate elements, one adapted to pivotally support clothes-drying racks and the other adapted to rest thereagainst whereby tension may be applied by one of said plates against the clothes-drying racks for preventing undesirable and free pivotal movement thereof.

Still a further object is to provide a pair of brackets each having a plurality of openings therein for pivotally receiving the ends of a plurality of clothes-drying racks and means spaced above and below said brackets in close relationship thereto whereby the ends of said cloth-drying racks may be received in the space between said brackets and said means whereby the ends of said clothes-drying racks are in frictional engagement with the brackets in which they are received.

The object of the invention is to improve the construction of such drying racks as to a considerable number of characteristic features, as will be hereinafter fully and clearly set forth.

In the accompanying drawings, forming a part of this specification, Fig. 1 is a front view in perspective of a clothes dryer embodying my invention. Fig. 2 is a side elevation of the base and a part of the standard in folded position. Fig. 3 is a fragmentary view of the same parts below the section line 3-3 of Fig. 1. Fig. 4 is a fragmentary side elevation of the rack and standard in the line 4-4 of Fig. 5. Fig. 5 is a fragmentary plan view of the rack below the section line 5-5 of Fig. 4. Fig. 6 is a fragmentary front elevation of one of the rack supports and the mounting of the same on the standard.

That portion of the dryer which carries the garments or fabrics to be dried may be briefly designated the rack. It comprises a supporting bracket and a group of arms pivoted thereto, to be spread out radially for drying purposes, or folded closely together

when not in use. The bracket comprises a wall (or post) plate 5, bent at right angles at the ends to form abutment-plates 6. Adjacent to the abutment-plates are set similarly shaped bearings 7, which are formed as stirrups, and riveted at 8 to the wall-plate. Both bearings and the wall-plate are pierced at 9 with a key-hole slot so as to hang on a pair of screws 10 in a supporting standard, either end up, and be easily and quickly attached or detached.

The rack-bars 11 are formed as long stirrups or loops from steel rods, with inturned terminals 12 to engage the bearings. The latter are pierced at 13 to receive said terminals, and in order that the rack-bars, when collapsed, may lie closely together, it is desirable to dispose the bearing holes diagonally, as best shown in Fig. 5. This admits of the holes being made without intersecting, and permits the bars to close together in a compact and practically parallel mass, for stowage in the house when not in use, and for saving of space in packing for shipment. Except for the buffer thimbles 14 attached at the looped ends, the rack-bars when so collapsed might lie perfectly parallel, and thus occupy the least possible space. The thimbles are short sections of rubber tubing, and are designed to prevent rubbing and abrasion of the rack-bar rods.

It is to be noted that each rack-bar forms a nearly complete rectangle, sharply bent at each corner. The effect of this, and the fourfold bearing, is to give the bar great stiffness vertically, and thus make possible the use of light rods in forming the rack, a matter of economy in manufacture and transportation, and convenience in handling when in use.

The bearings, as will be seen, are disposed between and close to the abutments, and are necessarily riveted to the wall-plate after assembling. Screws 15 connect the outer of each bearing-plate with the adjacent abutment, and thereby the respective plates may be adjusted to clamp the interposed rack-bars with as much or little tension as is necessary to keep them from swinging too loosely when spread apart.

For general use the rack is best mounted on a standard 16, herein shown as a straight wooden post, provided with supporting screws or studs 10, as above described. At 5 the lower end it is provided with a base of foldable and flaring legs projecting laterally and forwardly as does the rack when spread out. Two lateral legs 17 are attached pivotally by bolts 18 to a rectangular slide 19 fitting the post slidably. Braces 20 connect with the legs pivotally at 21 and the post at 22. A pair of forwardly extending legs 23 are connected by a bridge or cross-tie 24, and are pivoted by bolts 25 to the ends of the 15 slide, these and the other leg bolts fitting in countersunk holes, as shown in Fig. 3, so that the slide presents smooth surfaces to the standard. Braces 26 connect these legs pivotally with the lower end of the standard at 27 and 28, respectively, the downward movement of the slide is limited by a stop 29, so that in the position shown in Fig. 1 the legs formed a trussed base, with a three-point contact with the floor. The legs collapse to 23 positions parallel with the standard, as shown in Fig. 2, by simply sliding the slide and its connections upward on the standard.

The dryer is especially convenient in connection with the portable ironing boards in 33 general use. Its back may be set close to a wall, thus economizing space in the laundry. The ironing board may stand directly between the base and the rack, with no interference, when the rack is in the most convenient possible position to take the articles as folded and ironed.

It is to be noted that the vertical stiffness of the rack-bars, to which reference has above been made, is due in part to the quadruple, short-turn bends, and also to double 40 bearings for each pivot of the rack-bar which by prolonging the bearings impart a truss-like rigidity to the slender, rectangular structure. The form of the bar also 45 gives a double holding capacity, longer articles being held on the lower rod, and shorter ones above.

Having thus described my invention, I 50 claim:

1. In a clothes dryer, the combination of a skeleton rack-bar formed of rod bent to substantially rectangular form, with terminal, aligned pivots, bearing brackets pierced for said pivots, and a support for said brackets 55 having out-turned abutments to overlap the rod at the pivot bends and hold the pivots in bearing position.

2. In a clothes dryer, the combination of 60 a skeleton rack-bar formed of rod bent to substantially rectangular form, with terminal, inturned pivots, bearing brackets for said pivots, a support for said brackets having out-turned abutments to overlap the rod at the 65 pivot-bends, and means for applying clamp-

ing tension to said abutments with respect to the brackets and interposed rack-bar rod.

3. In a clothes dryer, the combination of a skeleton rack-bar formed of rod bent to substantially rectangular form, with terminal, 70 inturned pivots, a pair of double-bearing brackets engaged by said pivots, and a connected supporting plates having out-turned abutments to hold the pivots in bearing position, and pierced with key-hole slots for detachable connection with a supporting standard. 75

4. A clothes drying device comprising a vertical support, a pair of spaced brackets secured thereto, a plurality of clothes holding racks pivotally connected to and arranged between said brackets and means located between the point of securement of the brackets to the support and the pivotal connection of the racks to the brackets extending above and below said pair of brackets and secured thereto for applying tension against said racks for preventing free pivotal movement thereof. 85

5. A clothes drying device comprising a vertical support, a pair of spaced brackets secured thereto, a plurality of clothes holding racks pivoted between said brackets and means for applying tension against said brackets between said support and said racks for preventing free pivotal movement of the latter relative to the former. 90

6. A clothes drying device comprising a vertical support, a bracket secured thereto, a plate secured to said support in spaced relation to said bracket, adjustable means of connection between said plate and said bracket, a plurality of clothes supporting racks pivotally mounted in said bracket and extending into the space between said bracket and said plate, whereby tension may be applied to said 100 racks by adjusting said adjustable means of connection. 105

7. A clothes drying device comprising a vertical support, a bracket secured thereto, a plate secured to said support in spaced relation to said bracket, a plurality of clothes supporting racks pivotally mounted in said bracket and extending into the space between said bracket and said plate, said racks being in frictional engagement with said bracket 110 and said plate and a contractible connection between said bracket and said plate and located between said support and said racks for maintaining said racks so engaged with said bracket and said plate. 115

In testimony whereof I affix my signature.

STEPHEN A. SLAUSON.
